(57) **CLAIM**

The ornamental design for a graphical user interface for a wireless rain sensor, as shown and described.

DESCRIPTION

FIG. 1 is a first embodiment of a graphical user interface for a wireless rain sensor, where the graphical user interface of this embodiment indicates that both a rain threshold and temperature threshold have been met and irrigation is disabled; and,

FIG. 2 is a second embodiment thereof, where the graphical user interface of this embodiment indicates that a rain threshold has been met and irrigation is disabled.

The broken lines showing of the values of the battery indicator, the signal strength indicator and the pairing indicator, as well as the irrigation override indicator and the allow irrigation indicator in FIGS. 1 and 2, and the freeze indicator in FIG. 2 are for the purpose of illustrating unclaimed portions and form no part of the claimed design.
